HYMAN ELI GOLDBERG AND DAVID GOLDBERG, OF CHICAGO, ILLINOIS, ASSIGNEES TO
SELEX SPECIALTIES COMPANY, OF CHICAGO, ILLINOIS.

GARMENT-BAG.

1,097,544.

Specification of Letters Patent. Patented May 19, 1914.

Application filed May 15, 1911. Serial No. 827,326.

To all whom it may concern:

Be it known that we, HYMAN ELI GOLDBERG and DAVID GOLDBERG, citizens of the United States, residing at Chicago, in the 5 county of Cook and State of Illinois, have invented certain new and useful Improvements in Garment-Bags; and we do hereby declare the following to be a full, clear, and exact description of the invention, such as 10 will enable others skilled in the art to which it appertains to make and use the same.

This invention has for its object to provide a garment bag suitable for containing garments to protect the same against the 15 deposit of dust thereon and against attack by moths, and consists in the features of construction and combinations of parts hereinafter fully described and claimed.

In the accompanying drawings illustrating a garment bag embodying the invention: Figure —1— is a view in front elevation, partly broken away of a garment bag constructed in accordance with our invention. Fig. —2— is a fragmentary detail section 25 of the same on an enlarged scale on the line 2—2 of Fig. —1—. Fig. —3— is a horizontal section of the same on an enlarged scale on the line 3—3 of Fig. —1—. Fig. —4— is a fragmentary detail view in elevation showing an elastic closure employed. Fig. —5— is a detail perspective view of 30 one member of the closure employed.

Our invention has several objects, one thereof being to provide a garment bag 35 which is primarily cheap and convenient for use and which is adapted to contain a multiplicity of garments to be protected from dust and moths.

A further object of the invention is to provide a garment bag which may be hung on a suitable support, and which, while so supported, may receive garments and permit removal of the same without removing it from its support.

A still further object of the invention is to provide a supporting hook for garments or garment hangers within the bag which is so disposed relatively to the hook for supporting said bag as to cause the weight of 50 the inserted garments to throw the lower end of the bag in a direction opposing the direction of insertion of garments.

A further object of the invention is to provide simple and convenient means for

effecting closure and sealing of the bag between the intervals of insertion into and removal of garments from the same.

The bag may be made of any suitable material but is preferably made of paper. It consists of a rectangular receptacle A in the upper end of which a stick B of wood or other material is mounted, the latter serving to reinforce said upper end of the bag and to which the hook C for hanging said bag on a suitable supporting hook in a closet, or the like, is rotatably secured. A hook D upon which the garments or garment hangers are adapted to be supported within the bag is rigidly secured to the said stick B adjacent the attachment of the hook C therewith. The said bag is open along one longitudinal edge, the front and rear walls of the bag being folded along said edge to form flaps E and F respectively, which are adapted to be folded over to close or seal said open side edge. The opposite longitudinal edge of the bag is provided with an accordion plait G to render the same more readily expandable in a well-known manner. The upper and lower ends of the bag are sealed.

On the flap F, formed by the free portion of the rear wall of the bag, there is mounted one member H of a latch or closure. This consists of a hook of any suitable form attached in any convenient manner to said flap F. In the drawings we have illustrated the ordinary shoe lace hook having a shank which passes through the flap and is flanged over on its other edge in the usual way to secure said hook. Upon the front wall of the bag a similar hook I is mounted in a similar manner, the latter, as shown in Fig. —5—, being provided between its ends with an opening J through which the elastic loop K is adapted to pass. The loop K is made of the ordinary covered rubber elastic cut to a given length and the two end portions of which are engaged with each other by means of a metallic clasp L which, when contracted, prevents separation thereof. The said clasp L is of greater diameter than the opening J in the hook I so as to be incapable of passing through the same, said opening being, however, sufficiently large to permit the loop to be passed therethrough, as is shown in Fig. —3—.

The said hook D is off-set relatively to the

hook C toward the closed longitudinal edge or side of the bag so that when inserting a garment into the bag the weight of said garment when imposed upon said hook D, 5 will serve to throw the lower end portion of the bag in a direction opposed to the direction of insertion of the garment and thus increases the convenience of insertion, that is to say, the garment to be inserted is 10 usually disposed upon a garment hanger and the latter is grasped during insertion. Hence, the upper end portion of the garment will be forced into the bag but the frictional resistance to the insertion of the lower 15 end portion serves, generally, to cause the said lower end portion of the bag to recede and, therefore, after the garment hanger, upon which said garment is supported, has been hung upon the hook D it usually be- 20 comes necessary for the person to carefully insert the lower end portion of the garment into the lower end portion of the bag. By off-setting said hook D, as described, however, the weight of the garment on the hook 25 serves to automatically throw the bag back to its normal position and thus to automatically receive the lower end portion of the garment.

Our said bag is simple, cheap and extra- 30 ordinarily convenient for use, being readily opened and sealed and rendering the insertion and removal of garments easy.

We claim as our invention:

1. A device of the kind specified comprising a bag open along one longitudinal edge, 35 a reinforcing member in the upper end thereof from which the bag-body depends, a hanger for said bag secured to the middle portion of said reinforcing member, and a single member adapted to support a garment within the bag secured to said reinforcing member adjacent the point of attachment of said hanger therewith and farther from the open edge of the bag than 40 said hanger, the weight of a garment imposed upon said supporting member acting to tilt the bag to swing the open edge in a direction opposed to the direction of inser- 45

tion of said garment, substantially as described.

2. A device of the kind specified comprising a bag open along one longitudinal edge, a reinforcing member in the upper end thereof from which the bag-body depends, 50 a hanger for said bag secured to the middle portion of said reinforcing member, a single member adapted to support a garment within the bag secured to said reinforcing member adjacent the point of attachment of said hanger therewith and farther from the open 55 edge of the bag than said hanger, the weight of a garment imposed upon said supporting member acting to tilt the bag to swing the open edge in a direction opposed to the direction of insertion of said garment, and 60 means for effecting closure of the open edge of the bag to seal the same, substantially as described.

3. The garment delivery bag herein described comprising a bag like body portion 70 having a side opening at the extreme edge of the bag with the front portion of the bag extending approximately to the open side thereof and with the back portion of the bag provided with a flap extending laterally 75 over the front portion to a point in front of the bag and about the middle line thereof whereby a substantial closure flap is formed which extends sufficiently beyond the side opening to efficiently guard against the entrance of dust, fastening devices for securing the edge of said flap to the bag front, 80 means permanently closing the upper and lower ends of the bag and devices at the top and within and without the bag for coöper- 85 ating in suspending a garment within the bag and for suspending the bag and its contents.

In testimony whereof we have signed our names in presence of two subscribing wit- 90 nesses.

HYMAN ELI GOLDBERG.
DAVID GOLDBERG.
